UNITED STATES PATENT OFFICE.

FRIEDRICH AUGUST WOLFF, OF HEILBRONN, GERMANY.

APPARATUS FOR MANUFACTURING GELATINE AND GLUE.

SPECIFICATION forming part of Letters Patent No. 496,469, dated May 2, 1893.

Application filed April 22, 1892. Serial No. 430,247. (No model.)

To all whom it may concern:

Be it known that I, FRIEDRICH AUGUST WOLFF, a citizen of Würtemberg, residing at Heilbronn, in the Kingdom of Würtemberg, 5 Germany, have invented certain new and useful Improvements in Apparatus for Manufacturing Gelatine and Glue; and I do hereby declare the following to be a full, clear, and exact description of the invention, such as 10 will enable others skilled in the art to which it appertains to make and use the same.

This invention relates to the method and means for treating gelatine glue and similar substances, and its object is to avoid the 15 wastes and imperfections resulting from the methods heretofore employed for manufacturing these substances.

For this purpose my invention essentially consists in conducting the glue, &c., in a thin 20 continuous sheet along a path of sufficient length to enable the glue to harden and set sufficiently to be cut and deposited upon drying plates, which are then introduced into drying chambers, of any well known or suitable 25 arrangement for completing the drying of the glue. I preferably conduct the sheet of glue, &c., through a closed chamber, or casing, through which I conduct a current of air, by an exhaust or force pump, preferably, in 30 a direction opposite to that in which the sheet of glue is traveling.

In the accompanying drawings I have represented an apparatus which I consider the best in form to carry my invention into effect.

35 In the drawings, Figure 1, represents a vertical longitudinal section of the apparatus. Fig. 2, is a vertical transverse section on the line 2—2, Fig. 1; Fig. 3, a plan view partly in section, and Fig. 4, a transverse vertical section, 40 on an enlarged scale, through the casing and glue carrying apron, on line 4—4, Fig. 1.

A, represents the reservoir for holding the liquid glue. To the bottom thereof is connected the pipe a, provided with a cock a'. Upon 45 opening the cock a' the liquid glue flows out upon an endless belt C, running over the pulleys E' E². This arrangement is best shown in Fig. 1. The belt C is provided on its outer surface with a layer of wax-cloth B, or similar material having a smooth surface which 50 prevents the adhesion of the glue thereto.

This outer layer of wax-cloth, as shown in Fig. 4, overlaps or projects beyond the edges of the endless belt or apron C. In order to support the belt between the pulleys E' and E², and prevent its sagging, rolls or idlers c are arranged below the same at suitable intervals. The entire belt is inclosed within a suitable chamber or casing F. As will be noted by reference to Fig. 4, two horizontal strips or ledges b, whose forward ends are bent downwardly extend into the casing from the outer walls of the same near the top thereof. These ledges b, as will be readily understood by reference to Fig. 4, serve the purpose of raising and supporting the outer edges of the wax-cloth coating B, and thereby to form an endless trough for holding the liquid glue and preventing the same from running over the edges of the endless belt C. 70 As the belt passes over the pulley E² the same is reversed as shown at c', so as to bring the sheet of glue uppermost. The lower portion of the belt is also supported by rollers c, as shown. Before reaching the pulley E' the belt 75 C is again reversed, as at c², so as to return it to its original position. A stripper e, which may be a blade of steel or other suitable material, extends from the casing toward the belt, and serves to strip the sheet of glue or other 80 material, which has now sufficiently hardened, from the belt C, whose further progress deposits the sheet of glue upon an endless belt i, running over pulleys J, and which is arranged at a suitable point to receive the glue, 85 as shown. Above the belt i is arranged a rotary cutter G, preferably consisting of a transverse blade mounted on a pulley which derives its motion from the shaft of the pulley E', as shown. Below the belt i, is arranged 90 another endless belt k, which may also derive its motion from the shaft of the pulley E', and which may be of sufficient length to extend into the drying chamber. Upon this belt k, the operator deposits the drying plates 95 R upon which the tablets or cakes of glue are deposited as they leave the cutter G, as illustrated in Fig. 1. I preferably provide an air blast which passes over the surface of the sheet of glue in a direction contrary to its 100 travel. I preferably effect this by dividing the casing F into two compartments by a par-

tition F^3 , between the pulleys E' and E^2 , and within the belt C . The lower part of the casing is provided with an air inlet f^2 , while the upper portion of the casing F , is provided 5 with a duct f' leading to an exhaust fan or blower H , of any suitable form or construction.

The mode of operation of this apparatus is evident from the foregoing. The liquid glue 10 is deposited upon the belt C , in a film whose thickness may be accurately regulated by adjusting the speed of the belt C . As this sheet of film travels along on the belt it encounters the current of air, which serves to cool the 15 same and also to carry off the products of evaporation. As the sheet of glue arrives at the end of its path it is stripped from the belt by the stripper e and deposited upon the belt i to be subsequently cut into sections, or tab-

lets of suitable size by the cutter G , and 20 finally deposited upon the drying plates R .

What I claim, and desire to secure by Letters Patent, is—

In an apparatus for treating glue and the like, a movable apron for receiving the liquid 25 glue in combination with a stripper and a cutter for dividing the sheet of glue, an endless belt as, *i*, below the cutter and a third endless belt below the latter belt, adapted to carry the drying plates upon which the cakes of 30 glue are deposited after being cut, substantially as set forth.

In testimony whereof I affix my signature in presence of two witnesses.

FRIEDRICH AUGUST WOLFF.
